(57) **CLAIM**

The ornamental design for a conduit support, as shown and described.

DESCRIPTION

FIG. 1 is an isometric elevational view of an embodiment of the conduit support of the new design supporting a conventional conduit, which is shown in broken lines;

FIG. 2 is a front view of the conduit support depicted in FIG. 1;

FIG. 3 is a left side elevational view of the conduit support depicted in FIG. 1 with the right side elevational view being a mirror image thereof;

FIG. 4 is a top view of the conduit support of FIG. 1;

FIG. 5 is a bottom view of the conduit support of FIG. 1;

FIG. 6 is an isometric elevational view of another embodiment of the conduit support of the new design;

FIG. 7 is a front view of the conduit support depicted in FIG. 6;

FIG. 8 is a left side elevational view of the conduit support depicted in FIG. 6 with the right side elevational view being a mirror image thereof;

FIG. 9 is a top view of the conduit support depicted in FIG. 6; and,

FIG. 10 is a bottom view of the conduit support depicted in FIG. 6.

The broken lines showing conduits, nuts, washers and support members in FIGS. 1–10 depict an environment for illustrative purposes only and form no part of the claimed design.
